Primary Examiner — Ian Simmons*Assistant Examiner* — Carissa C Fitts*(74) Attorney, Agent, or Firm* — Schwegman Lundberg & Woessner, P.A.(57) **CLAIM**

The ornamental design for a tool shield, as shown in FIGS. 1-6 and described.

DESCRIPTION

FIG. 1 is a right and top side perspective view of a tool shield showing my new design;

FIG. 2 is a left plan view of the tool shield of FIG. 1;

FIG. 3 is a right plan view of the tool shield of FIG. 1;

FIG. 4 is a top plan view of the tool shield of FIG. 1;

FIG. 5 is a front end view of the tool shield of FIG. 1; and,

FIG. 6 is a rear end view of the tool shield of FIG. 1.

The broken line showing is for environmental purposes only and forms no part of the claimed design.
